(57) **CLAIM**

I claim the ornamental design for an irrigation controller control panel, as shown and described.

DESCRIPTION

FIG. 1 is a front perspective view of a control panel of an irrigation controller in which a rotary dial, buttons, an alarm indicator, and pins are illustrated in broken lines for illustrative purposes and form no part of the claimed design; FIG. 2 is a rear perspective view thereof in which cable guides, various connectors, bays and structural features are illustrated in broken lines for illustrative purposes and form no part of the claimed design; FIG. 3 is a front view thereof; FIG. 4 is a left view thereof; FIG. 5 is a right view thereof; FIG. 6 is a top view thereof; FIG. 7 is a bottom view thereof; and, FIG. 8 is a rear view thereof.

1 Claim, 5 Drawing Sheets
